United States Patent Office

Des. 222,241
Patented Oct. 12, 1971

222,241

AUTOMOBILE BODY

Frederick M. Does, 4205 Wedgmont Circle S.,
Fort Worth, Tex. 76133

Filed May 18, 1970, Ser. No. 23,039

Term of patent 14 years

Int. Cl. D12—08

U.S. Cl. D14—3

FIG. 1

FIG. 2

FIG. 3

FIG. 4

FIG. 5

FIG. 6

FIG. 1 is a front elevation view of an automobile body embodying my new design;

FIG. 2 is a rear elevation view of said body;

FIG. 3 is a plan view of said body;

FIG. 4 is a side elevation view of the said body, the right and left sides of the body being identical;

FIG. 5 is a perspective view as seen from the front and right side of the body; and

FIG. 6 is a perspective view as seen from the rear and left side of the body.

I claim:

The ornamental design for an automobile body, as shown and described.
